UNITED STATES PATENT OFFICE.

HAROLD A. WEBSTER, OF HAVERHILL, MASSACHUSETTS, ASSIGNOR TO
HERBERT B. NEWTON, OF HAVERHILL, MASSACHUSETTS.

ROTARY EDGE-SETTER.

SPECIFICATION forming part of Letters Patent No. 687,417, dated November 26, 1901.

Application filed December 17, 1900. Serial No. 40,121. (No model.)

To all whom it may concern:

Be it known that I, HAROLD A. WEBSTER, of Haverhill, in the county of Essex and State of Massachusetts, have invented certain new

5 and useful Improvements in Rotary Edge-Setters, of which the following is a specification.

This invention relates to machines or devices for setting and burnishing the sole edges of boots and shoes; and it consists in the novel 10 features of construction and relative arrangement of parts hereinafter fully described in the following specification, clearly illustrated upon the accompanying sheet of drawings, and particularly pointed out in the claim.

15 Reference is to be had to the accompanying drawings, forming a part of this application, in which like characters indicate like parts wherever they occur.

In the drawings, Figure 1 represents a side 20 elevation of a rotary edge-setter constructed in accordance with my invention. Fig. 2 represents a front elevation of the same. Fig. 3 represents a section through the operating-rolls on the line 3 3 of Fig. 1 looking in the 25 direction of the arrow. Fig. 4 represents a vertical sectional view on the line 4 4 of Fig. 2 looking in the direction of the arrow.

In my copending application, Serial No. 1,231, I have shown, described, and claimed, 30 broadly, my new rotary edge-setter and have also claimed one form thereof.

This application covers that particular species of my new rotary edge-setter wherein the rolls or pins have a movement of translation 35 around a common axis, but do not rotate on their own axes.

1 represents a portion of a standard or bracket of an edge-setter.

2 represents a shaft carried by a bearing 30 on the end of the bracket 1.

4 represents a pulley fast upon one side of said shaft and arranged to be rotated by a belt 5.

6 represents my rotary edge-setter secured 45 to the free end of the shaft 2. The shaft at its free end is reduced, as at 10.

The holder 11 of the edge-setter is shown as a collar slid upon the reduced part 10 of the shaft 2. This holder carries pintles 12, arranged in circular form, and on the free end of each pintle 12 is mounted a setting-roll 13,

the pintles 12 and the rolls 13 being fast to the holder 11 and adapted to be driven thereby in a circular path, although the rolls 13 have no motion of rotation.

55

14 represents a flange resting upon the ends of the rolls 13.

15 represents a screw by which the holder, rolls, and flange that comprise the setter are securely fastened to the reduced end 10 in 60 order that the setter may be driven in unison with the shaft.

It will be observed that the rolls 13 are separated or spaced from each other and from the holder, so that air can be circulated in 65 and about the rolls, thus enabling them to be driven at great speed without burning. These rolls as they wear may be adjusted to bring a new face into operative position. This may be done by turning them forcibly on their pintles when they are driven on a circular pintle or by removing them from the pintles, depending upon the manner in which the roll is secured to the pintle and depending somewhat upon the manner in which the pintle is secured to the holder. It will also be observed 70 that the rolls 13 rest upon a reduced shoulder 16 of the holder.

17 represents the outer end of the holder formed as a collar against which the flange 14 80 bears, said collar 17, as shown, being separated from the rolls 13. The outer end of the holder or collar 17 has no particular function, so far as the rolls 13 are concerned, other than that it is necessary to have said collar separated from the rolls by an air-space, the purpose of the collar 17 being as an abutment 85 against which the flange 14 strikes.

While I prefer to have the rolls of a circular form for cheapness of construction, yet 90 my invention is not limited to such shape, as I may use a roll having a different form in cross-section than a circle without departing from the spirit and scope of my invention, which includes, in the present case, a rotary 95 edge-setter comprising a holder equipped with a fixed set of setting-rolls spaced from each other.

Having thus explained the nature of the invention and described a way of constructing and using the same, although without attempting to set forth all of the forms in which

it may be made or all of the modes of its use, I declare that what I claim, and desire to secure by Letters Patent, is—

An edge-setter comprising a holder and series of setting-rolls, rigidly secured to said holder and driven thereby, and means for adjusting said rolls.

In testimony whereof I have affixed my signature in presence of two witnesses.

HAROLD A. WEBSTER.
